DISPENSING CABINET FOR PAPER TOWELS

Charles E. Kirch, Buffalo, N. Y.

Application September 23, 1937, Serial No. 165,359

11 Claims.

(Cl. 312—58)

This invention relates to improvements in cabinets for dispensing interfolded paper towels of the kind which are arranged in a pack so that the leading ends of alternate of the towels are located at one side of the pack while the leading ends of the intermediate towels are located at 5 the opposite side of the pack.

One object of the invention is to provide a cabinet which is so designed that waste is minimized by preventing the rapid uninterrupted withdrawal of successive towels.

A further object is to provide a cabinet in which the towels are wholly contained until just before their withdrawal.

15 A still further object is to provide for simplicity and economy in construction.

The invention is illustrated in the accompanying drawings in which:

Figure 1 is a perspective view of a cabinet embodying the features of the invention.

Figure 2 is a vertical section taken along line 2—2 of Figure 1.

Figure 3 is a section taken along line 3—3 of Figure 2 showing the positions of the parts before the cabinet is conditioned to enable the withdrawal of a towel.

Figure 4 is a similar section showing the positions of the parts after the cabinet has been conditioned to enable the withdrawal of a towel.

30 Figure 5 is a section taken along 5—5 of Figure 1, the parts being shown in the same positions as in Figure 4 with the leading towel partially withdrawn.

Figure 6 is a similar section and shows the 35 positions of the parts after the succeeding towel has been moved to an accessible position.

Figure 7 is a fragmentary section taken along line 7—7 of Figure 3.

The cabinet, as illustrated, includes a cover section 10 and a back section 11, the latter being 40 formed with forwardly directed flanges 12. The cover section is pivotally mounted upon the said flanges by rivets 13 and is normally secured in its closed position by a lock 14, the opening movement of the cover section being limited by pins 15 which are carried by the flanges 12 and which traverse arcuate slots 16.

The towels which are indicated at 17 are withdrawn through an opening 18 formed in the bottom wall of the cover section. They are arranged in a magazine 19 which includes side walls 20 and 21. The said walls are suitably secured to the back section 11; they are spaced inwardly with respect to the flange 12; and they carry a bottom wall 22 upon which the towels are supported over a central opening 23. The towels are interfolded in conventional manner. One section of each is arranged between the sections of the towel above it while the other section is arranged between the sections of the towel

below it, the leading ends of alternate of the towels extending beyond one side of the opening 23 while the leading ends of the intermediate towels extend beyond the opposite side of the said opening. When they are arranged in the 5 magazine 19 the leading end of the lowermost towel is directed through the opening 23 and is inserted between members 24 and 25. The said members are located below the magazine opening and are carried by arms 26 and 27 which are 10 suspended for pivotal movement from pins 28 and 28a which are carried by the side walls of the magazine. The said arms include cross-pieces 29 and 29a, the latter being provided with a laterally extending flange 30 which is formed 15 with a slot 31. An actuating lever 32 is pivotally mounted upon the pin 28a, the lower end of the said lever extending through the slot 31 and being connected by a rod 33 to one end of a spring 34. The other end of the spring is connected to a 20 bracket 35 which is carried by the side wall 21 of the magazine. In Figure 3 the spring 34 is illustrated holding the parts at one limit of their range of movement. When the said parts occupy such positions the leading end of the lowermost 25 towel extends through the opening 23 and across and above the outlet opening 18 toward the front wall of the cover section 10.

The upper end of the actuating lever 32 is 30 formed at one side of the pin 28a with an elongated slot 36 which extends lengthwise of the lever, the said slot being so formed that the pin 28a is located substantially midway between its ends. The slot provides a guideway for an offset extension 37 which is formed or provided 35 upon a link 38 (see Fig. 7). The latter is connected by a pin 39 to the lower end of a link 40, the upper end of the latter being suspended for pivotal movement by a pin 40a from the wall 21. A spring 41 connects one end of the link 38 to a 40 bracket 42 which is mounted upon the wall 21 and is operative to urge both links toward the front wall of the cover section.

When it is desired to withdraw a towel from the cabinet a button 43 is pushed. The movement of 45 the button is transmitted by a stem 44 to a lateral extension 45 which is carried by the link 40. The links 38 and 40 are thus caused to move toward the rear wall of the cabinet against the action of the spring 41. Assuming the parts to occupy 50 the positions shown in Figure 3, this movement is transmitted to the lever 32 by the link extension 37. The lever 32 is thus caused to move in a counter-clockwise direction. The initial part of such movement is resisted by the spring 34. 55 When the lever 32 passes dead center, however, the spring 34 is rendered operative to complete its movement and to hold it in its new position. During the initial part of the counter-clockwise movement of the lever 32 its lower end moves 60

along the slot 31, thereby permitting the arms 26 and 27 to remain stationary. During the final part of such movement, however, its lower end engages an end of the slot 31 so that its further movement is transmitted to the arms 26 and 27. The said arms are thus caused to move to the opposite limit of their range of movement as shown in Figure 4. As the arms 26 and 27 move toward such positions the member 24 directs the leading end of the lowermost towel downwardly so that it is caused to move through the opening 18 to a position in which it may be readily grasped. It will be noted further that the movement of the links 38 and 40 to actuate the lever 32 in the manner described increases the tension on the spring 41. However, as the said lever approaches the position shown in Figure 4 the upper end of the slot 36 is inclined toward the front wall of the cover section, thereby permitting the spring 41 to move the link extension 37 to the upper end of the said slot and thus return the link 40 to its original position.

The towel which has been rendered accessible in the manner described may be readily withdrawn from the cabinet. During such withdrawal it passes around the under side of the member 24, pulling the leading end of the succeeding towel down through the opening 23 and against the member 24 as best shown in Figure 5. As the accessible towel is completely withdrawn from the cabinet the leading end of the succeeding towel tends to return to its original shape as indicated in dotted lines. The succeeding towel, therefore, remains wholly within the cabinet and its leading end is inaccessible through the opening 18. When it is desired to withdraw the succeeding towel the button 43 must be again operated. When the button is pushed the second time the links 38 and 40 are operative to move the actuating lever in a clockwise direction. The initial part of such movement is against the action of the spring 34 and is not transmitted to the arms 26 and 27 owing to the movement of the lever in the slot 31. As the actuating lever passes dead center and engages the forward end of the slot, however, its further movement in response to the spring 34 is transmitted to the arms 26 and 27 and they are moved to their original positions, namely the positions shown in Figure 6. During such movement the member 25 directs the leading end of the succeeding towel through the opening 18 to a position in which it may be readily grasped, it being understood that as the said towel is withdrawn the leading end of the succeeding towel is withdrawn from the magazine 19 to assume the position shown in Figure 3. It will be noted that as the lever 32 approaches its original position the lower end of the slot 36 is again inclined downwardly toward the front wall of the cover section, thereby enabling the spring 41 to move the extension 37 of the link 38 to the lower end of the said slot and thus return the links 38 and 40 to their original positions.

From the foregoing it will be apparent that the button 43 is operative when first actuated to effect movement of the members 24 and 25 in a counter-clockwise direction and is operative when again actuated to effect movement of the said members in a clockwise direction. Hence when one towel is withdrawn the leading end of the succeeding towel may be extended to an accessible position. It will be noted in this connection that the movement of the button 43 is utilized, regardless of the direction of movement of the actuating lever, to move the said lever beyond

dead center so that the spring 34 may be availed of to complete such movement, the slot 31 being so formed that the movement of the actuating lever is transmitted to the arms 26 and 27 only after it passes dead center. Only one towel can then be withdrawn from the cabinet at a time, it being necessary to again operate the button 43 if a second towel is desired. The cabinet, therefore, has the advantage that indiscriminate withdrawal of the towels is thus prevented without inconveniencing successive users. A further advantage obtained is that the lowermost towel in the magazine is protected in a large measure and hence is preserved in a good condition even though not withdrawn for a substantial period of time.

I claim as my invention:

1. A cabinet for dispensing paper towels, a magazine in which said towels are adapted to be folded and arranged in a pack so that the leading ends of alternate of said towels are located at one side of said pack while the leading ends of the intermediate towels are located at the opposite side of said pack, said cabinet having an opening in one wall through which said towels are adapted to be withdrawn, said magazine supporting the foremost towel so that its leading end is spaced from said opening, a member which is located between said magazine and said opening and which is movable between two limits and means for effecting movement of said member first to one of said limits and then to the other, said member being operative as it is moved toward one of said limits to advance the leading end of the foremost towel through said opening and being operative when the foremost towel has been withdrawn and it is moved toward the other of said limits to advance the leading end of the succeeding towel through said opening.

2. A cabinet for dispensing paper towels, a magazine in which said towels are adapted to be folded and arranged in a pack so that the leading ends of alternate of said towels are located at one side of said pack while the leading ends of the intermediate towels are located at the opposite side of said pack, said cabinet having an opening in one wall through which said towels are adapted to be withdrawn, said magazine supporting the foremost towel so that its leading end is spaced from said opening, a member which is located between said magazine and said opening and which is movable between two limits, resilient means for holding said member at either of said limits and means for effecting movement of said member first to one of said limits and then to the other, said member being operative when it is moved to one of said limits to advance the leading end of the foremost towel through said opening and being operative when the foremost towel has been withdrawn and it is moved toward the other of said limits to advance the leading end of the succeeding towel through said opening.

3. A cabinet for dispensing folded paper towels, a magazine in which said towels are adapted to be arranged in a pack so that the leading ends of alternate of said towels are located at one side of said pack while the leading ends of the intermediate towels are located at the opposite side of said pack, said cabinet having an opening in one wall through which said towels are adapted to be withdrawn, said magazine supporting the foremost towel so that its leading end is spaced from said opening, a member which is located between said magazine and said opening and which is pivotally mounted for movement between two limits, resili-

- is operative when first actuated to move said lever in one direction beyond dead center and which is operative when again actuated to move said lever in the opposite direction beyond dead center and means providing a lost motion connection between said lever and said first named means, whereby the movement of said lever is transmitted to said first named means only after said lever has been moved beyond dead center.
9. A cabinet for dispensing folded paper towels, said cabinet having an opening in one wall through which said towels are adapted to be withdrawn, a magazine in which said towels are arranged in a pack so that the leading ends of alternate of said towels are located at one side of said pack while the leading ends of the intermediate towels are located at the opposite side of said pack, said magazine supporting the foremost towel so that its leading end is spaced from said opening, means which is suspended for swinging movement below said magazine and which is formed to provide a passage in which the leading end of the foremost towel is positioned, a lever mounted for oscillation between two limits, a spring which is connected at one end to said lever and at its opposite end to a fixed part of said cabinet and which is operative to complete the movement of the latter to either of said limits after it moves beyond dead center, said lever being operative as it is moved in one direction to move said means to advance the leading end of the foremost towel through said opening and being operative after the foremost towel is withdrawn and it is moved in the opposite direction to move said means to advance the leading end of the succeeding towel through said opening, a manually operable element carried by a part of said cabinet, links associated with said element and lever, said links being operative when said element is first actuated to move said lever in one direction beyond dead center and being operative when said element is again actuated to move said lever in the opposite direction beyond dead center.
10. A cabinet for dispensing folded paper towels, said cabinet having an opening in one wall through which said towels are adapted to be withdrawn, a magazine in which said towels are arranged in a pack so that the leading ends of alternate of said towels are located at one side of said pack while the leading ends of the intermediate towels are located at the opposite side of said pack, said magazine supporting the foremost towel so that its leading end is spaced from said opening, means which is suspended for swinging movement below said magazine and which is formed to provide a passage in which the leading end of the foremost towel is positioned, a lever mounted for oscillation between two limits, a slot, a spring which is connected at one end to said lever and at its opposite end to a fixed part of said cabinet and which is operative to complete the movement of the latter to either of said limits after it moves beyond dead center, said lever being operative as it is moved in one direction to move said means to advance the leading end of the foremost towel through said opening and being operative after the foremost towel is withdrawn and it is moved in the opposite direction to move said means to advance the leading end of the succeeding towel through said opening, a manually operable ele-

ment, connected links which are actuated by said element, carried by a part of said cabinet, one of said links having a projection which has a sliding fit in said slot and the other of said links being pivotally connected to a fixed part of said cabinet, resilient means for normally holding said links so that they will be actuated when said element is operated, said links being operative when said element is first actuated to move said lever in one direction beyond dead center, said slot assuming a position as said lever is moved in such direction to permit said resilient means to move said projection to one end of said slot and thereby return one of said links to its original position, said links being operative when said element is again actuated to move said lever in the opposite direction beyond dead center, said slot assuming a position during such movement of said lever which will permit both of said links to return to their original positions.

11. A cabinet for dispensing folded paper towels, said cabinet having an opening in one wall through which said towels are adapted to be withdrawn, a magazine in which said towels are arranged in a pack so that the leading ends of alternate towels are located at one side of said pack while the leading ends of the intermediate towels are located at the opposite side of said pack, said magazine supporting the foremost towel so that its leading end is spaced from said opening, means which is located below said magazine and which is formed to provide a passage in which the leading end of the foremost towel is positioned, depending pivotally mounted arms for carrying said means, one of said arms being formed with a guideway, a lever mounted for oscillation between two limits, one end of said lever extending through said guideway while a slot is formed in the opposite end, a spring connected at one end to said lever and at its opposite end to a fixed part of said cabinet and which is operative as said lever moves beyond dead center and engages an end of said guideway to move said means to advance the leading end of the foremost towel through said opening and which is operative after the foremost towel is withdrawn and said lever is moved in the opposite direction to engage the opposite end of said guideway to move said means to advance the leading end of the succeeding towel through said opening, a manually operable element carried by a part of said cabinet, connected links which are actuated by said element, one of said links having a projection which has a sliding fit in said slot, and the other of said links being pivotally connected to a fixed part of said cabinet, resilient means for normally holding said links so that they will be actuated when said element is operated, said links being operative when said element is first actuated to move said lever in one direction beyond dead center, said slot assuming a position as said lever is moved in such direction to permit said resilient means to move said projection to one end of said slot to return one of said links to its original position, said element being operative as it is again actuated to move said lever in the opposite direction beyond dead center, said slot assuming a position during movement of said lever in this direction which will permit both of said links to return to their original positions.

CHARLES E. KIRCH.
